CONTAINER FOR LIP STICKS AND
THE LIKE

Alex Limbach, Carmel, N. Y.

Application May 22, 1934, Serial No. 726,942

3 Claims. (Cl. 206—56)

This invention relates to containers designed primarily for use with lipsticks although it will be apparent that the nature of the element carried therein is immaterial. The principal object of 5 the invention is to provide an improved container having novel mechanism for operating a carrier for the material and opening and closing the container in desired timed relation to the movements of the carrier. The improved mechanism is characterized principally by simplicity, cheapness, 10 compactness and the provision of a maximum travel for the carrier in a container of minimum dimensions. More particularly, the invention has for its object to provide an actuator for the carrier which shall be movable about a fixed axis, 15 the preferred embodiment taking the form of an operating disk or its equivalent, rotatable within the container to advance and retract the carrier. A further object of the invention is to incorporate 20 in an actuator having the characteristics indicated an operating element so related to the axis of movement of the actuating member that it will impart to the carrier a travel of approximately twice the effective range of movement of the 25 operating element itself. More particularly, this object is obtained by providing a cam surface which is so related to the carrier and to the axis of movement of the actuating member that the carrier will be given a travel of approximately 30 twice the length of the cam itself.

A further object of the invention is to provide a container of circular form in which the carrier and associated mechanism is housed, the container itself being very compact and handy and 35 by means of the improved operating mechanism adapted to carry a pomade stick or the like which may be of a length substantially equal to the diameter of the container and yet be readily expelled from the container to the desired maximum extent.

A further object of the invention is to associate the closure for the container with the actuating member so that "automatic" operation is obtained, meaning that the opening through which 45 the pomade is expelled is automatically opened before its movement begins and is subsequently closed after its complete retraction.

The invention will be described more particularly in connection with the embodiment shown 50 in the accompanying drawing which is intended to be merely illustrative, and in which:

Figure 1 is a view in side elevation of the improved container made in circular form and showing a finger operating piece.

Figure 2 is a view in end elevation of the con-

tainer shown in Figure 1 with the pomade fully expelled.

Figure 3 is a view in end elevation of the container shown in Figure 2.

Figure 4 is a view in elevation showing the inner face of the actuating member.

Figure 5 is a view in end elevation of the operating member illustrated in Figure 4, a part being broken away to show the slot.

Figure 6 is an interior view in elevation of the improved container with the actuating member removed, the slot being indicated in dotted lines merely to show its relation to the carrier when the actuating member is assembled.

Figure 7 is a view similar to Figure 6 showing 15 the relation of the slot to the carrier when the carrier is substantially fully advanced.

Figure 8 is a view in vertical section through the container shown in Figure 1 and taken on the plane indicated by the line 8—8 of Figure 1 20 and looking in the direction of the arrows.

Figure 9 is a view in vertical section through the container shown in Figure 2 and taken on the planes indicated by the broken lines 9—9 and looking in the direction of the arrows. 25

Figure 10 is a view in horizontal section taken through the container shown in Figure 1 on the plane indicated by the line 10—10 and looking in the direction of the arrows.

It will be apparent to one skilled in the art 30 as the description proceeds, that the improved container need not be circular in form nor need the actuating member to be described in connection with the illustrated embodiment comprise a circular disk rotating about a fixed central axis. The same mode of operation in accordance with the novel principles set forth herein can be accomplished in containers of other 35 superficial form and with actuating members that are not disks. However, it will be apparent 40 that the invention rests on certain principles involving certain relationships between the elements and while the appended claims are intended to cover equivalent structures embodying such principles they are not intended to cover 45 other structures in which such principles are not to be found.

In the form shown the container proper comprises a back wall *a* having a circular end wall *a'* interrupted at *a*² to provide an opening 50 through which the pomade *b* or other element can be expelled. The front wall of the container comprises a plate *c* which has a circumferential segmental wall *c'* adapted to be nested within the circular wall *a'* of the container and re- 55

tained rotatably therein but against axial displacement as by turning over slightly the edge a^3 of the circular wall a' . Any suitable form of operating finger piece shown as a diametrically extending rib c^2 may be carried on the outer face 5 of the plate c to permit convenient rotation thereof in either direction. When the pomade or other material is housed within the container the segmental wall c' will extend across the opening a^2 so as to constitute a closure therefor whereas 10 when the pomade is to be expelled, rotation of the plate c will carry the segmental wall c' away from the opening and the interrupted portion of this wall is of such circumferential length as to 15 be in registry with the opening a^2 during the entire travel of the pomade.

Within the container is mounted a back plate d which in the illustrated embodiment is circular in form to conform to the shape of the back wall a . The plate d may have struck out therefrom segmental flanges d' which are bent into parallelism so as to constitute a track in which the carrier e for the pomade is slidably mounted. The plate d , of course, is fixed with 20 respect to the back wall a so that it cannot rotate and the carrier e is thus required to move in a fixed path.

The carrier e has secured thereto a pin b' which is off the center line of the carrier. In 30 the illustrated embodiment the carrier has a laterally extending flange b^2 to which this pin is secured. On the rear face of the plate c is secured a disk f . This disk has formed therein an arcuate slot f' which is concentric with the periphery of the disk, that is to say, the arc is struck from the axis of the disk, indicated at f^2 . When the carrier e is in its fully retracted position the pin b' , which is engaged with the slot f' , is adjacent one end thereof. Rotation of the 35 disk f through rotation of the plate c by the finger piece c^2 is permitted by reason of the concentric character of the slot f' in which the pin b' is disposed. It is to be understood that the disk f is fixed relatively to the plate c so as to 40 rotate therewith. In fact, the slot f' might be formed directly in the plate c , if desired. The parts are so related that when the carrier is fully retracted as illustrated in Figure 6 the segmental 45 circumferential wall c' carried by the plate c overlies the opening a^2 in the container and closes it. However, when the plate c is rotated through the distance which finds the pin b' riding in the slot f' the said circumferential wall c' will be carried away from the opening a^2 so 50 that the pomade is free to be expelled there-through. The slot f' at one end extends radially of the disk f as indicated at f^3 . The exact form of this portion of the slot is not essential since it may be somewhat curved or may extend along 55 a true radius of the disk. However, it is regarded as important that the portion f^3 of the slot shall not extend generally to the left of the axis f^2 of the disk as viewed in Figure 4 when the disk, as viewed in Figure 4, is to be rotated in a 60 counterclockwise direction. As viewed from the front of the plate c (Figure 1), the slot f^3 should not extend to the right of the axis f^2 , the plate being rotatable in a clockwise direction, to 65 expel the pomade. Continued rotation, however, of the disk f will carry the pin b' out of the portion f' of the slot and bring it into communication with the radially extending portion f^3 . The outer edge f^4 of this portion of the slot may be regarded as a cam surface so far as concerns its 70 action on the pin. When this edge deviates from 75

a line concentric with the axis f^2 of rotation of the disk a component of force will be impressed on the pin b' in such direction as to urge the carrier e along its track formed by the flanges d' . As the rotation of the disk f continues the operating edge f^4 of the slot will move the carrier e forwardly, as viewed in Figure 6. The pin b' will reach its closest position to the axis f^2 of rotation of the disk at the moment that the pin and said axis lie in a plane at right angles to the axis of movement of the carrier. The portion f^3 of the slot is so designed that at that moment the pin b' may be located near the inner end of the slot f^3 . Continued rotation of the disk will exert pressure on the pin b' through the edge f^4 of the slot still causing the carrier e to continue its outward travel. However, the pin b' as viewed with relation to the slot f^3 will recede from the end of the slot and travel towards the arcuate portion f' . Such relationship is indicated in Figure 7 where the carrier e is shown in such position that the pomade b is fully exposed beyond the side wall of the container. When the plate c is rotated in a counterclockwise direction as viewed in Figure 1 (that is to say, when the disk f as viewed in Figure 4 is rotated in a clockwise direction) the actuating force will be transmitted through the other edge f^5 of the slot f^3 to the pin b' to move the carrier inwardly, the pin ultimately finding itself opposite to the arcuate slot f' when the carrier is fully retracted. At this moment, the interrupted edge of the circumferential wall c' approaches the opening a^2 . Continued rotation of the plate c will serve to bring this segmental wall c' over the opening a^2 to 25 close the container and the parts will eventually come to rest with the pin b' at the end of the slot f' as indicated in Figure 6.

From the description given it will be evident that the opening of the container with relation to the actuation of the carrier is so related as to constitute what is commonly termed an "automatic" action. The edge f^4 of the slot f^3 which is termed a cam, in that its action on the pin b' is that of a cam, is so disposed in the operating element that it causes the pin to travel rectilinearly a distance substantially twice the length of the cam itself. This is obviously a very desirable condition because it enables the parts to be made very compact and the pomade to be of a length equal substantially to the diameter of the container. Compactness, simplicity, cheapness and maximum travel for the pomade with relation to the dimensions of the container are primary factors.

I claim as my invention:

1. A container for a lipstick or the like having an opening through which the material is movable, a carrier for the material movable rectilinearly within the container, an actuating disk rotatable about its central axis, means to rotate the disk, a slot in the disk extending generally radially thereof, a pin mounted on the carrier offset from the central axis of the carrier and engaging said slot whereby rotary movement of the disk imparts rectilinear movement to the carrier.

2. A container for a lipstick or the like having an opening through which the material is movable, a carrier for the material movable rectilinearly within the container, an actuating disk rotatable about its central axis, means to rotate the disk, a slot in the disk extending generally radially thereof, a pin mounted on the carrier offset from the central axis of the carrier and

engaging said slot whereby rotary movement of the disk imparts rectilinear movement to the carrier, the said slot being so disposed with relation to the carrier and the axis of rotation that 5 rotation of the disk causes movement of the carrier for a distance greater than the effective operating length of the slot.

3. A container for a lipstick or the like having an opening through which the material is movable, a carrier for the material movable rectilinearly within the container, an actuating disk 10

rotatable upon a central axis, means to rotate the disk, a slot in the disk extending generally radially thereof, a pin mounted on the carrier offset from the central axis of the carrier and engaging said slot whereby rotary movement of the disk imparts rectilinear movement to the carrier and causes the pin to move in the slot toward the axis of the container and subsequently in the continued motion of the disk causes the pin to move outwardly in the slot. 5

ALEX LIMBACH. 10
